UNITED STATES PATENT OFFICE.

VICTOR HERBERT BARR-SMITH, OF NEUTRAL BAY, NEAR SYDNEY, NEW SOUTH WALES, AUSTRALIA.

COMBINED COLLAPSIBLE COAT HANGER AND TROUSERS PRESS.

Application filed July 2, 1927, Serial No. 203,233, and in Australia April 13, 1927.

This invention relates to a combined coat-hanger and trousers-press usable for either purpose or for both. The article is so constructed that it may be readily assembled for 5 use as a combination article or collapsed to render it suitable for travelling or storage purposes.

Referring to the accompanying drawings in which the invention is illustrated, Fig. 1 is 10 a perspective view of the trousers-press of the article; Fig. 2 a longitudinal section of the trousers-press; Fig. 3 perspective detail view of hinge bracket means for the coat-hanger; Fig. 4 perspective view of the trousers-press and coathanger combined; Fig. 5 15 detail view illustrative of the hinge bracket means and associative coathanger; Fig. 6 phantom view of combined article collapsed and enclosed within a travel case.

20 The article comprises two tapering members each consisting of a series of elements 1 and 2 hinged at 3 and 4 to one another, and adapted either to lie over each other or to be folded separately. Fixed on the tapering 25 edges of each of the elements 1 is an angle plate 5 provided with a bifurcated lug 6. Adapted to engage with each of such lugs 6 are separate clamping bolts 7 hinged at 8 to angle plates 9 secured to the tapering edges 30 of the elements 2. Cooperating with said bolts 7 are securing nuts 10.

When the article is to be used as a trousers-press, the series of members 1 is removed from the other series of members 2 and the folded trousers may then be located between both 35 series of such members. After the trousers have been placed on one series of such members and the removed members are placed over the trousers situated on the other members; the elements 1 and 2 of both said members may then be fastened to each other by 40 securing the clamping bolts 7 to the lugs 6 through the nuts 10 whereby the trousers will be pressed between the two said members. Upon loosening the nuts 10 of the clamping 45 bolts 7 one series of members 1 of the article is detachable from the other series 2 thereof and the pressed trousers may then be removed from the article.

50 If the article is to be used as a combined coathanger and trousers-press, the hinged members 1 and 2 of the article are attached to a coathanger 11 provided with anchor oppositely disposed pins 12 adapted to enter

openings 23 in plates 13 hinged at 14 to opposite edges of one of the series of elements 2. Such hanger 11 is made in two portions which are hinged at 15 to each other and carry a folding ring 16 attachable to a support. Temporary lock buttons 17 are provided on one of the members 1, the plates 18 being also secured respectively on the oppositely disposed edges of one of such members; the buttons 17 are adapted to enter 55 openings 19 in the plates 13 when such plates are folded to such edges to receive the anchor pins 12, the latter being carried by angle plates 20 attached to the hanger 11 which is formed to receive such plates 20. Preferably the plates 13 have an offset 21 to enter recesses 22 therefor in one of the elements 1.

Should the article be desired for travelling or storage purposes, the members 1 and 2 and the coathanger 11 thereof are separated and each of them is folded on their respective hinges when the whole will be of suitable size to be carried in a travelling case 24 or for storage. The members 1 and 2 and coathanger 11 are shown collapsed and located in a travelling case in Fig. 6.

To remove the coathanger 11 from the trousers-press it is only necessary to press the plates 13 outwardly from the members 1 and 2, when the anchor pins 12 will be removed from the said plates 13 and the coathanger 11 will thus be free to be folded on its hinge member 15. The portions 25 of the coathanger 11 are inclined to adapt them to fold closely to each other when the parts of the coathanger are to be collapsed. The plates 13 90 may be folded to the element 1 when the coathanger 11 has been removed therefrom.

What I claim as my invention and desire to secure by Letters Patent is:—

1. A combined collapsible trousers-press and coathanger comprising a first series of tapering elements hinged to each other, a second series of tapering elements hinged to each other, lug carrying plates on the first series of said elements, securing bolts with cooperating nuts hinged to the second series of said elements and respectively adapted to engage the respective lugs on the first series of said elements, plates hinged to one of the elements of the second series of elements each of said plates having an opening therein, a foldable coathanger with oppositely disposed pins thereon adapted when said coathanger is 95 100 105

to be attached to said trousers-press to enter the said openings, the said coathanger being detachable from said trousers-press.

2. A combined collapsible trousers-press and coathanger according to claim 1, to which is secured to the opposite edges of one of the elements forming the first series of hinged tapering elements a projection adapted to en-

ter an opening in the plates hinged to one of the elements of the second series of said hinged tapering elements when the latter plates are closed to the former plates on the edges of the elements of the said first series of elements. ¹⁰

In testimony whereof I affix my signature.
VICTOR HERBERT BARR-SMITH.
